UNITED STATES PATENT OFFICE.

HOMER PENDLETON, OF KOKOMO, INDIANA, ASSIGNOR OF ONE-HALF TO MARGARET A. SPAULDING, OF KOKOMO, INDIANA.

ELECTRICALLY-ILLUMINATED FOUNTAIN-PEN.

1,188,311.

Specification of Letters Patent. Patented June 20, 1916.

Application filed January 26, 1915. Serial No. 4,512.

To all whom it may concern:

Be it known that I, HOMER PENDLETON, a citizen of the United States, residing at Kokomo, in the county of Howard and State 5 of Indiana, have invented certain new and useful Improvements in Electrically-Illuminated Fountain-Pens; and I do hereby declare the following to be a full, clear, and exact description of the invention, such as 10 will enable others skilled in the art to which it appertains to make and use the same.

This invention relates to an illuminated fountain pen, and the primary object of the invention is to provide a fountain pen with 15 an illuminating attachment, whereby a person may use the pen in a dark place, and avoid mistakes by illuminating the paper upon which the pen is used.

Another object of this invention is to provide a fountain pen as specified, which includes an outer retaining casing having a battery positioned therein, electric conductors extending longitudinally through the casing and communicating with a lamp 25 socket, and to position an incandescent bulb in said socket in close proximity to the writing point of the fountain pen, which point has communication with an ink feeding mechanism and retaining tube.

With the foregoing and other objects in view, this invention consists in such novel features of construction, combination and arrangement of parts, as will be hereinafter more fully described, illustrated in the accompanying drawings, and claimed.

In describing the invention in detail, reference will be had to the accompanying drawings, wherein like characters designate like or corresponding parts throughout the 40 several views, and in which;

Figure 1 is a longitudinal section through the improved fountain pen, Fig. 2 is an enlarged view of the lamp retaining socket and the mechanism connected thereto for connecting the socket to the battery, and Fig. 3 is an end view of the writing end of the fountain pen.

Referring more particularly to the drawings, 1 designates the outer casing of the pen, which is substantially cylindrical in shape, having its forward end 2 tapered inwardly, as is clearly shown in Fig. 1 of the drawings. The rear end of the cylindrical casing or tube 1 is open, for permitting of 55 the insertion or removal of a battery 3 into

the casing. The battery 3 has pins 4 and 5 communicating with the negative and positive poles of the battery, respectively, which pins are seated in the ends of electrical conducting tubes 6 and 7. The tubes 6 and 7 are preferably constructed of copper, to increase their electrical conductive proclivities. The tubes 6 and 7 are supported within the casing 1 by a bracket 8, which is secured to the inner surface of the casing in any suitable manner, and which is provided with openings extending therethrough, in and through which the tubes 6 and 7 extend. The tube 6 extends forwardly longitudinally within the casing 1, and has its forward end 60 secured to an angle member 9. The angle member 9 is constructed of electric conducting material and is secured to the casing, being held against the inner surface of the same by means of a screw or other analogous 65 fastening device 10. The angled arm 11 of the angle member 9 extends through the insulating housing 12 of an ordinary lamp socket 13, and it is connected to the inner electrical conductive lamp plug receiving 70 socket 14, as is clearly shown in Fig. 2 of the drawings.

The tube 7 extends parallel with the tube 6, and has its forward end connected to a pin 15, which extends centrally through the insulating housing 12, and has a head 16 positioned upon its inner end, which head is insulated from the socket 14 by a disk 17 of insulation, so that when the plug indicated at 18, of an electrical incandescent 75 light bulb 19 is inserted into the socket, and the central electrode of the plug engages the head 16 of the pin 15, a circuit will be closed through the poles of the battery 3, and ignite the light 19.

When it is desired to extinguish the light 19, the same is rotated within the socket 13 until the central electrode of the plug 18 moves out of engagement with the head 16, which breaks the circuit and extinguishes 100 the lamp. The casing 1 has an ink retaining tube 20 positioned therein and extending longitudinally thereof, which ink retaining tube has a self-filling mechanism 21, of any desired type associated therewith, for filling 105 the tube with ink. The forward end of the tube 20 is positioned toward the forward tapered end 2 of the casing, and it has a pen point 22 connected thereto, and suitable ink feeding mechanism 23, for feeding the ink 110

from the tube 20 to the point of the pen 22, for writing purposes, as is ordinary in the construction of fountain pens. A cap 24 is provided for forming a protector for the 5 pen 22 and the light 19, as is indicated in dotted lines in Fig. 1 of the drawings. In the use of the pen, the cap 24 is inserted upon the rear battery carrying end of the casing 1.

10 When it is desired to use the pen in a dark place, the light 19 is rotated within the socket 13, until the inner end of the plug 18 thereof engages the head 16, which closes the circuit through the poles of the battery 15 3 and ignites the light, illuminating the papers upon which the pen 22 is used.

In reducing the invention to practice certain minor features of construction, combination and arrangement of parts may necessitate alteration, to which the patentee is 20 entitled, provided such alterations are comprehended within the scope of what is claimed.

What is claimed is:—

25 In an illuminating fountain pen, a protecting casing, a fountain pen structure including a pen point positioned within said

casing, an electrical battery mounted in one end of said casing, an electric lamp socket positioned in the other end of said casing 30 and in close proximity to said pen point, an incandescent light bulb seated in said socket, an angle member located within the casing and having one arm thereof inserted into said socket and secured thereto for communicating with one pole of said light bulb, fastening means extending through the wall of the casing and engaging the other arm of the angular member, a tube connected to said last mentioned arm of the angled member and 40 to one pole of said battery, a second tube connected to the opposite pole of said battery and to the opposite pole of said incandescent light bulb for closing a circuit through said socket and said incandescent 45 light bulb, and a bracket arm depending from the interior of the casing and having openings therein for receiving the tubes.

In testimony whereof I affix my signature in presence of two witnesses.

HOMER PENDLETON.
